US00D741160S

(12) **United States Design Patent**
Hendricks et al.

(10) **Patent No.:** **US D741,160 S**
(45) **Date of Patent:** **** Oct. 20, 2015**

(54) **FENCE CLIP**

(71) Applicants: **Richard L. Hendricks**, Atkinson, NE (US); **Mike Fredrick**, Atkinson, NE (US)

(72) Inventors: **Richard L. Hendricks**, Atkinson, NE (US); **Mike Fredrick**, Atkinson, NE (US)

(73) Assignee: **Box T Brand, LLC**, Atkinson, NE (US)

(**) Term: **14 Years**

(21) Appl. No.: **29/478,487**

(22) Filed: **Jan. 6, 2014**

(51) **LOC (10) Cl.** **08-08**

(52) **U.S. Cl.**
USPC **D8/394**
